BURGLAR ALARM

James R. Harmon, 6845 SW. 17th St., Miami, Fla., and Harold G. Schneider, 8867 Carlyle Ave., Surfside, Fla.

Filed Aug. 29, 1962, Ser. No. 71,488

Term of patent 14 years

(Cl. D72—1)

FIG. 1

FIG. 2

FIG. 3

FIG. 4

FIG. 1 is a perspective view of our burglar alarm showing our new design.

FIG. 2 is a side elevation thereof.

FIG. 3 is a bottom view thereof.

FIG. 4 is a top view thereof.

The undisclosed side is a mirror image of the side shown and the rear is plain.

The dominant features of the design are shown in full lines.

We claim:

The ornamental design for a burglar alarm, as shown and described.
